UNITED STATES PATENT OFFICE.

WILLIAM E. DODSON AND ELMER E. POWELL, OF CHECOTAH, OKLAHOMA, ASSIGNEES
OF ONE-THIRD TO B. E. ROSENDAHL, OF CHECOTAH, OKLAHOMA.

AUTOMOBILE ATTACHMENT.

1,208,927.

Specification of Letters Patent. Patented Dec. 19, 1916.

Application filed January 28, 1916. Serial No. 74,919.

To all whom it may concern:

Be it known that we, WILLIAM E. DODSON and ELMER E. POWELL, citizens of the United States, residing at Checotah, in the county of McIntosh, State of Oklahoma, have invented certain new and useful Improvements in Automobile Attachments; and we do hereby declare the following to be a full, clear, and exact description of the invention, such as will enable others skilled in the art, to which it appertains to make and use the same.

This invention relates to improvements in attachments for automobiles and particularly to devices for drawing automobiles out of sandy or muddy places, and to assist in drawing automobiles up steep inclines.

The principal object of the invention is to provide a novel and simple device of this character which can be readily applied to the ordinary automobile, and which will be effective for the purpose designed.

Another object is to provide a novel and efficient device of this character which, when attached to an automobile, forms a permanent part thereof and which can be quickly and easily thrown into and out of operative position for actuation by the engine shaft, of the automobile.

Other objects and advantages will be apparent from the following description when taken in connection with the accompanying drawing.

In the drawing: Figure 1 is a plan view of a portion of an automobile showing our invention applied thereto; Fig. 2 is a front elevation; Fig. 3 is a horizontal section through the device; Fig. 4 is a vertical section on the line 4—4 of Fig. 3; Fig. 5 is a vertical section on the line 5—5 of Fig. 3; Fig. 6 is a sectional view showing the winding drum and shaft tilted to disengage the actuating gears; Fig. 7 is a vertical longitudinal sectional view through a modified form of the device; and Fig. 8 is a vertical section on the line 8—8 of Fig. 7.

Referring particularly to the accompanying drawing, 10 represents a casing mounted on any suitable part of the automobile, but in close proximity to the engine shaft 11. On the engine shaft is mounted a worm gear 12, the same being adapted to rotate with the shaft. Extending longitudinally in the casing 10 is a shaft 13, and on this shaft, within the casing is a winding drum 14, on which

is wound a cable 15. One end of the shaft 13 is mounted in a bearing block 13' loosely disposed in an opening in the adjacent end of the casing. Secured to one end of this drum is a pinion 16 which meshes with the pinion 17 mounted on a shaft 18 parallel with and adjacent one end of the drum and this pinion is rigidly connected to and rotatable with a second and larger pinion 19. The drum and pinion 16 are loosely mounted on the shaft 13, and rigidly mounted on the shaft 13 outwardly of the pinion 16, and meshing with the pinion 19 is a smaller pinion 20. Thus the rotation of the shaft 13 communicates motion to the drum from the gear 20 to the gears 19 and 17 and back to the gear 16. This arrangement of gears produces a reduction in speed, while at the same time greatly increasing the driving power of the shaft 13 on the drum. In the other end of the casing 10 is an opening 21 in which is rotatably mounted a block 22 which receives the adjacent end of the shaft 13 eccentrically therethrough. On the last-named end of the shaft 13, and outwardly of the casing 10 is a spiral gear 23 which meshes with the before-mentioned wheel 12 carried by the engine shaft.

Mounted on the eccentrically disposed end of the shaft 13 inwardly of the casing and secured to the block 22 is an arm 24, the outer end of which is connected to a shifting lever (not shown) by a rod 25 and by means of which the arm may be moved to rotate the block 22 within the opening 21 for the purpose of shifting the position of the adjacent end of the shaft 13 and thus move its gear 24 toward and away from the gear 12.

In the operation of the device, one end of the cable 15 is drawn to a point in advance of the automobile and secured to a stake driven in the ground, or to a tree, post, or other fixed object. The gears 12 and 23 being engaged by movement of the arm 24, the engine is started which results in the winding of the cable on this drum 14 and the pulling of the automobile out of the muddy or sandy place in the road or up a steep incline. As soon as the automobile is out of the undesirable place, the arm 24 is shifted back again so as to move the shaft 13 and thus disengage the gears 23 and 12. The engine of the automobile is then run to drive the automobile, in the usual manner.

Referring particularly to Figs. 7 and 8

there is shown a casing 10', in which is mounted a shaft 13' carrying a drum 14', and on which is wound a cable 15'. One end of the shaft 13' is eccentrically mounted in the block 22', said block being arranged in an opening 21' in the casing and actuated by a lever 24'. All of these parts are identical in construction to the corresponding parts of the other form. The other end of the shaft 13' is mounted in a bearing block 13'' which is disposed in an opening in the end of the casing. It will be noted that in this form of the device the gears 16, 17, 19 and 20 are omitted.

15 What is claimed is:

An attachment for an automobile comprising a casing mounted on the frame of the automobile adjacent the engine shaft thereof, a shaft rotatably mounted in the casing,

a drum rotatably mounted on the shaft, a 20 pinion carried by the drum and rotatable therewith, a pinion carried by the shaft and rotatable therewith and disposed adjacent the drum pinion, a pair of rigidly connected and simultaneously rotatable pinions mounted 25 in the casing and each meshing with one of the before-mentioned pinions, intergeared connections between the shaft and the engine shaft of the automobile, and an eccentrically mounted means for canting the drum shaft 30 to disengage the intergeared connections.

In testimony whereof, we affix our signatures in the presence of two witnesses.

WILLIAM E. DODSON.

ELMER E. POWELL.
